UNITED STATES PATENT OFFICE.

JAMES McCULLOCH, OF GLASGOW, SCOTLAND, ASSIGNOR OF ONE-HALF TO JOSEPH O'NEIL, OF HOLYOKE, MASSACHUSETTS.

STOKER FOR FURNACES AND BOILERS OF THE UNDERFEED TYPE.

1,113,569.

Specification of Letters Patent.

Patented Oct. 13, 1914.

Application filed October 12, 1912. Serial No. 725,510.

To all whom it may concern:

Be it known that I, JAMES McCULLOCH, a subject of the King of Great Britain, residing at Glasgow, Scotland, have invented 5 new and useful Improvements in Stokers for Furnaces and Boilers of the Underfeed Type, of which the following is a specification.

This invention relates to improvements in 10 stoves and furnaces of the type in which the fuel is fed from below or what is commonly known as the underfeed type wherein the fresh fuel is forced upwardly into the fire box and at the same time ashes or consumed 15 fuel is partially pushed downward through the grate into the ash pan. In external appearance it resembles the type known as the Latrobe stove that is designed to be placed in the wall of a house, the forward part of 20 the furnace or stove projecting into the room.

Referring to the drawings,—Figure 1 is an exterior side view of the completed stove in which the feed lever with its ratchet 25 mechanism is shown. Fig. 2 is a vertical sectional view through the furnace taken at right angles to the axis on which the coal pushers are mounted and showing the cam action for forcing the coal pressers outward 30 and withdrawing them as they leave the rear end of the fire box. Fig. 3 is a perspective view of one of the detached coal presser elements showing the cam construction by means of which it is forced downward and 35 withdrawn during the rotary movement of the shaft. Figs. 4 and 5 are detail views of the cam member which causes the movements of the coal pushers.

Referring to the drawings in detail *a* designates the forward part of the stove and *b* the rear part or section, the two sections being secured together by any suitable means as bolts shown at *c*. The forward section *a* is provided with doors indicated at *d* that 45 are hinged to the front section at the point *e* by means of which they may be opened and closed as desired.

f designates buttons or catches that have a threaded stem *g* for holding the doors in a 50 closed position. When it is desired to open the doors these catches are turned into the dotted line position shown at *f*.

Located back of the doors is the fire box or grating *h*. This, as shown in Fig. 2, is 55 substantially one-quarter of a circle or 90°;

the forward edge of which is curved as indicated at *i*. The lower part of the grate which extends rearwardly rests on the bottom of the forward section and against the front edge of the rear section as shown at *j*. An 60 ash pan is indicated at *k* by means of which the ashes may be conveniently removed from the stove. It is understood that when the doors *d* are open that the ash pan *k* can be removed and also the grate *h* if desired. 65 The products of combustion which pass from the fire-box *m* pass upward in the space *o* back of the doors, and through the opening *p* to the smoke flue *q*. A damper *r* is inserted in this flue for controlling the rate of com- 70 bustion.

The coal supply which is contained in the hopper *s*, is introduced through the inlet *t* that is closed by means of a cover *u*. The fuel which is preferably of a fine grade of 75 coal is stored in the rear of the presser wheel indicated as a whole by the letter *v*. This presser wheel is made up of a spider construction, the spokes of which are indicated at *w* and in the construction shown there are 80 four of them. The outer ends of these spokes are formed with curved arc-shaped portions *x* which have a horn or inwardly extending portion *y*. Mounted on the horn portions *y* so as to move readily are the presser members 85 *z*, the construction of which is clearly shown in Fig. 3. These presser members are adapted to be forced outward and drawn inward toward the axis of the wheel when the shaft *4* is rotated by the feed lever *5*, 90 which feed lever carries a pawl *6* to engage the teeth *7* of the ratchet wheel *8*. A second pawl *9* is shown attached to the casing to prevent the rearward movement of the shaft 95 *4* during the feeding operation. As shown in Fig. 2, the inner portion of the shaft is made rectangular and passes through a correspondingly shaped opening in the hub of the spider of the feeder wheel, whereby when the shaft *4* is turned the feed wheel 100 100 and the pushers will be rotated.

Referring to the construction of the coal pressers as shown in Fig. 3 it will be noticed that the edge *10* of these pressers is formed with the same radius of curvature as the arc-shaped members *x* of the presser wheel and that when these pressers are withdrawn they will lie within the periphery of the wheel. 105 These coal pressers have a recess *11* that receives the horn-shaped member *y* of the 110

spider and about which the coal pressers turn when moved outward as the presser wheel is rotated. 12 designates a stop portion on the lugs 13 to limit the outward movement of the coal pressers by engaging the end of the arc-shaped members α . The lugs 13 also serve as cam-surfaces to move the presser members 3 outward as will be described. At one side of these stops are shown lugs 14 which engage the projections 18 of the fixed cams 14' which are fixedly secured to the rear casing b by means of the arm 16 and right angular end portions 17. The fixed cams 14' are formed with two cam-surfaces 15 and 15'. The lugs 14 as they engage the projections 18 are moved into the retracted position until they reach the point shown in Fig. 2 where they will be forced outward as illustrated, the outward position serving to force the coal forward and into the grate at the lower part of the same. Rotation of the shaft 4 by the lever 5 causes the portion 14 to engage the projections 18, whereby the coal presser 3 is retracted into the position shown at 3¹ and it retains this position until it is again brought into use to feed a fresh supply of coal to the fire.

In Fig. 2 is shown a partition or division plate between the chamber σ and the coal hopper s , the same is designated at 19 and consists of a plate which extends from the passage p down to and above the feed wheel where it extends forward as indicated at 20. 21 designates a fire brick that covers this plate and serves to confine the heat to the forward part of the stove and prevent its being conducted to the coal hopper s . It will be seen from this construction that the stove is very simple in construction and one that could be manufactured very cheaply and also one that could be readily installed for heating purposes. If desired the plate 21' may be removed and the smoke flue inserted at this point. It is of course, understood that the coal is pushed forward through the opening 22 into the fire box at m .

It should be stated that when the coal presser elements 3 are in operation that the part 11¹ serves as a pivot about which it rotates on the portion α . It is also noticed that the shape of the cross-sectional end of the presser 3 is symmetrical, that is to say the arc-shaped sides 10 and 10¹ are equal which is the same radius as the portion α . The cam surface 15 which is of shorter radius than the cam-surface 15' serves to allow a space for the lugs 14 to travel in to normally maintain the pressers 3 extended until withdrawn.

22 designates an opening for supplying air to the fuel which may be closed by suitable covers.

Referring to the manner in which the pressers 3 are forced or moved outward when the handle 5 is operated, the edges 13' of the cam 13 ride upon the cam-surfaces 15' of the fixed cam 14' and are thereby gradually moved outward into the position shown in Fig. 2. They are retained in this outward position until the lugs 14 engage the projections 18 when the pressers 3 are retracted into a position to coincide with the periphery of the feeder wheel. 75

What I claim, is:—

1. In a stove of the underfeed type, the combination, a forward and a rear section united together, a partition to divide the two sections to form a coal hopper and the heating section, a feed wheel mounted in the lower part of the coal hopper, means for rotating the feed wheel to advance the fuel through a passageway leading from the coal hopper to the fire box portion of the heating section, said feed wheel having a spider portion, the outer ends of the spokes of which are made arc-shaped, coal presser elements having arc-shaped recesses and mounted on the arc-shaped portions of the spokes, two lugs formed on the presser elements, means to project and withdraw the coal presser elements when the said wheel is rotated, said means comprising a fixed cam to engage one of the lugs on the coal pressers to project the presser elements and a projection on the fixed cam engaged by the other lug on the presser elements to cause the retraction of said coal pressers after the coal has been advanced to the fire box as described. 95

2. In an underfeed stove or furnace, the combination, a wheel device for feeding coal to the fire-box portion, curved projections on the wheel device, means for rotating said wheel, coal presser elements adapted to be extended beyond and drawn into the general curved surface of the wheel, said elements having curved recesses therein to receive the projections of the wheel device and about which said elements are adapted to be oscillated, fixed cams to cause the presser elements to be forced outward, each of the presser elements having lugs to engage the periphery of the cam surface, 110 and interengaging projections on the cam, and coal presser elements to cause the same to be retracted, as described. 115
